Primary Examiner — Zenia I Bennett(74) *Attorney, Agent, or Firm* — Creativenture Law, LLC; Kevin C. Staed; Dennis J M Donahue III(57) **CLAIM**

The ornamental design for a jewelry clasp, as shown and described.

DESCRIPTION

FIG. 1 is an upper perspective view of a jewelry clasp;

FIG. 2 is a lower perspective view thereof;

FIG. 3 is a side view thereof;

FIG. 4 is a top view thereof; and,

FIG. 5 is a bottom view thereof.

The broken lines in FIGS. 1-5 illustrate an eyelet and chain that connect to the top and bottom ends of the jewelry clasp. Further, the additional broken lines in FIGS. 1-3 illustrate a fastening mechanism for fastening and unfastening the jewelry. These broken lines form no part of the claimed design.
